UNITED STATES PATENT OFFICE.

KONRAD LANGER, OF BALTIMORE, MARYLAND.

TELESCOPIC SMOKE-STACK.

1,283,817.

Specification of Letters Patent.

Patented Nov. 5, 1918.

Application filed November 26, 1917. Serial No. 204,007.

To all whom it may concern:

Be it known that I, KONRAD LANGER, a citizen of the United States, and a resident of Baltimore, in the State of Maryland, 5 have invented a new and useful Improvement in Telescopic Smoke-Stacks, of which the following is a specification.

My invention relates to an improvement in telescopic smoke stacks, and it consists in 10 the constructions, combinations, and arrangements herein described and claimed.

An object of my invention is to provide a telescopic smoke stack adapted primarily for use on ocean going vessels, which includes jackscrew and gear devices for raising the extensible section, said devices being located externally of the stack so as to be protected from the stack gases, but also so located as to be protected from the weather. 15

Another object of the invention is to provide a stack as described, including a housing for the jackscrew and gear devices, to shield said devices both from the stack gases and the weather. 20

Another object of the invention is to provide equi-distantly located jackscrew and gear devices, for applying the lifting power to the extensible stack member, uniformly. 25

Another object of the invention is to provide an indicator whereby the height to 30 which the extensible stack member has been raised, may be ascertained.

Other objects and advantages will appear in the following specification, reference 35 being had to the accompanying drawings, in which:

Figure 1 is a vertical section of the preferred form of the telescopic stack showing the extensible member elevated.

Fig. 2 is a similar view showing the extensible member telescoped.

Fig. 3 is a cross section on the line 3—3 of Fig. 2.

Fig. 4 is a vertical section of a slightly 45 modified form of the stack.

Fig. 5 is a cross section on the line 5—5 of Fig. 1, and

Fig. 6 is a detail view of the indicator.

In carrying out my invention, I provide 50 a stationary stack section 1 over which an

extensible or telescopic stack section 2 slides. The stationary stack section 1 is inclosed in a stationary tube 3 which is spaced therefrom to leave an air space 4. The extensible stack section 2 carries a tube 5 which is telescopic in the stationary tube 3. The various tubes and stack sections are held in spaced relationship by any suitable means, expansion joint 6 being provided between the stack section 2 and the tube 5 at the top. 55

The lower end of the stationary stack section 1 sets upon the outlet from the furnaces and is held in place in any suitable manner. The manner of mounting the stack is, however, of secondary importance in the present 60 instance, and so the illustration has been omitted. The stack projects through an opening 7 in the deck 8 of the vessel. The opening 7 is surrounded by a casing or flange 9. The stationary tube 3 carries an 70 umbrella 10 which is riveted to the stationary tube. The umbrella 10 has a sloping top which terminates in an annular vertical flange extending below the plane of the top edge of the casing or flange 9. The purpose 75 of the umbrella 10 is to deflect moisture in the shape of rain or snow, and other foreign elements so that they may not enter the opening 7.

The extensible stack section 2 carries a 80 hood 11 at the top, which extends over and covers the entrance to the space 12 between the stack section 2 and the tube 5. The rim of the tube 5 is reinforced by an annular angle iron 13, to which eye-bolts and 85 shackles 14 are attached. Guy wires are secured in the shackles. The function of the guy wires is, to brace the stack against wind pressure when it is in the extended position. When the stack section 2 and 90 tube 5 are telescoped, the guy wires are not necessary. In this case, the guy wires simply collapse, it being understood, that when the stack is again extended, the wires are drawn taut.

The extensible stack section 2 is elevated by a plurality of jackscrews 15 which are equi-distantly located in circumferential relationship in the space 4. Each of the jackscrews 15 has a bevel pinion 16 on the bot- 95 100

tom with which another bevel pinion 17 meshes. The bevel pinions 17 form the driving elements for the jackscrews 15, being in turn rotated through counter-shaft 5 and gear connections 18 and 19 driven from a motor 20. It will be evident that each of the jackscrews 15 is individually driven. Each jackscrew is rotated at a uniform rate of speed, and it therefore follows that the 10 lifting power is applied to the extensible stack section 2 uniformly and at equi-distantly located places.

Screw blocks 21 are fixed at proper intervals in the space 12 at the bottom of the 15 extensible stack section 2 and the tube 5. The jackscrews 15 are threaded into these blocks and project above the blocks a short distance as at 21^a, when the stack section 2 occupies the limit of its extension. The projecting end 21 of each jackscrew 15, enters the lower end of a pipe 22 which acts as a guide for the jackscrew when the stack section 2 is being lowered. There are four of these pipes, one for each jackscrew. The 20 pipes 22 are supported at the top by a suitably arranged bracket 23.

The indicator illustrated in Fig. 6, is provided so that the operator may tell how high the extensible stack section 2 is projected 30 out of the stationary section 1. The indicator comprises a movable pointer 24 which is threaded on one of the jackscrews 15 near the motor 20. The pointer 24 is held from turning, by engaging a guide 25 which has a 35 calibrated dial 26 over which the pointer plays. As the jackscrew 15 is rotated, the pointer 24 moves up and down and indicates the distance to which the extensible stack section 2 stands projected, according to the 40 direction of rotation of the jackshaft. Obviously, an automatic cut-off mechanism may be embodied in the indicator. This, however, is a feature which it is not sought to embody in the present subject matter, although it may be stated that an arrangement 45 of an electric circuit closer for breaking the motor circuit may readily be embodied to stop the motor when the pointer reaches either extremity of its movement.

50 The form of the telescopic stack illustrated in Fig. 4, is substantially the same as that illustrated in Fig. 1. The exception is, that the tube 5 on the extensible stack section 2, is omitted. This makes a lighter stack. In 55 this construction, it is necessary to provide the removable umbrella or hood 27 which is made in halves so that it can be removed. When the stack section 2 is extended, the hood 27 is placed and clamped in position, as shown in Fig. 4. Before the stack section 2 can be lowered, the hood 27 must be removed, whereupon the stack section 2 may be lowered to the desired position. The hood 27 is then again clamped over the en-

trance to the space 4 between the section 1 65 and the tube 3, to prevent the entrance of foreign elements to the space.

The operation of the device will be readily understood from the following when taken in connection with the foregoing description. The telescopic stack is intended primarily for use on ocean vessels. Heretofore, a telescopic smoke stack has not been necessary. The reason for the absence of this necessity is due to the fact that not until 75 the present time has the low visibility of ships on the ocean been desirable. This condition has been brought about by the danger to ships passing through the "war zone" where danger of attack is ever imminent. From this it will be understood, that the purpose of the whole invention is to decrease the visibility of the ship and render the passage more safe, this decrease in the visibility of the ship being directly 80 accomplished by the use of the telescopic smoke stack hereinbefore described. Obviously, the ability to lower the smoke stack from its normal extended height to its telescoped position, representing a difference of 85 approximately twenty feet, materially decreases the visibility of the vessel. If it be found advisable to telescope the smoke stack, the jackscrews 15 are operated simultaneously and at the same rate of speed by the 90 motor 20. The stack section 2 then telescopes into the stationary stack section 1. The tube 5 surrounding the section 2, also telescopes into the stationary tube 3. As the 95 stack section 2 moves downwardly, the upper ends of the jackscrews 15 become free and would tend to vibrate were it not for the provision of the pipes 22 which receive the jackscrews 15 and act as guides therefor.

The use of either of the forms of the invention illustrated in Figs. 1 and 4 is optional. As stated above, the stack structure shown in Fig. 4 is lighter because of the absence of the tube 5 surrounding the extensible stack section 2. In this form, however, the hood 27 must be taken off and replaced each time the stack is adjusted. In the preferred form of the invention shown in Fig. 1, this is not necessary. The hood 105 11 moves with the extensible section 2 and the tube 5 and section 2 move together. It should be explained that in the form illustrated in Fig. 4, the upper ends of the jackscrews 15 are supported in bearings 15^a. These are the equivalents of the pipe guides 120 22 in Fig. 1. As incidental features of construction, all of the joints of the plates used in the stack sections are butt joints. By the use of flush riveting on the sliding surfaces of the sections, very little clearance need be 125 allowed between the stationary and extensible stack sections.

It is desired to emphasize the simultaneous

and uniform operation of each of the jack-screws, whereby a uniform and simultaneous lifting power is exerted on the extensible stack sections and at equi-distantly located 5 points. This obviously prevents binding and insures the rapid extension of the stack sections.

While the construction and arrangement of the device as illustrated in the accompanying drawings, is that of a generally preferred form, obviously modifications and changes may be made without departing from the spirit of the invention or the scope 10 of the claims.

15 I claim:

1. A telescopic stack comprising a double walled stationary stack section, a double walled extensible stack section slidable between the walls of the stationary stack section, and means for raising and lowering 20 said extensible section, located between said walls out of contact with the stack gases.

2. A telescopic stack comprising a stationary stack section, an extensible stack 25 section slidable thereover, means for raising and lowering said extensible section, located exteriorly of the sections out of contact with the stack gases, and means inclosing said raising and lowering means, to protect the 30 latter from the elements.

3. A telescopic stack comprising a stationary stack section, an inclosing tube concentric with and spaced from said stack section, an extensible stack section slidable over 35 the stationary section, an inclosing tube concentric with and spaced from the extensible stack section, and slidable inside of said stationary tube, and means for raising and lowering the extensible stack section and 40 tube, located in the space between said sections and tubes.

4. A telescopic stack comprising a double walled stationary stack section, a double walled extensible stack section slidable 45 between the walls of the stationary stack section, a plurality of jack screws located between the stationary walls of the stationary stack section, screw blocks receiving said jackscrews and carried by the extensible 50 stack section, and means carried by said extensible stack section for receiving the ends of the jackscrews and acting as guides therefor, upon telescoping the stack.

5. A telescopic stack comprising a stationary stack section, an extensible stack section slidable thereover, screw blocks carried by the extensible stack section, jackscrews adjacent to the stationary stack section and received by the screw blocks, and 55 motor and gear devices for rotating the jackscrews simultaneously and at the same rate of speed, to apply the power for lifting the extensible section uniformly.

6. In a stack, the combination of a sta-

tionary stack section, an extensible stack 65 section slidable thereon, means located externally of the stack sections for elevating the extensible stack section and located out of contact of the stack gases, means for housing said elevating means to shield it from 70 the weather, and means for guiding said elevating means.

7. In a stack, the combination of a stationary stack section, an extensible stack section slidable thereon, a screw block carried 75 by the extensible stack section, a jackscrew located exteriorly of the stationary stack section and threaded in the screw block, the upper end thereof projecting beyond the screw block, and a pipe receiving the projecting end of the jackscrew to prevent vibration thereof on telescoping the extensible stack section.

8. In a stack, the combination with the deck of a vessel having an opening and a flange surrounding the opening, of a double walled stationary stack section projecting through said opening, an umbrella carried by the outer wall and covering said opening, a double walled extensible stack section 90 slidable between the walls of the stationary stack section, section extending means located between the respective walls, and a hood mounted on one of the walls of the extensible section and covering the space between the walls at the top to exclude the elements from said means.

9. In a stack, the combination of stationary and extensible stack sections, means for raising and lowering the extensible sections including a jackscrew, a pointer, screw 100 threaded on the jackscrew and movable up and down thereon according to the rotation of the jackscrew, and a guide for the pointer preventing it from rotating, said guide having calibrations for indicating the height of the extensible stack sections.

10. In a stack, a double walled stationary section, an extensible stack section slidable in the space between said walls, motor 110 driven extending means situated at the base of the stationary section, and a plurality of jackscrews driven by said means and extending into engagement with the extensible section, said jackscrews being located equidistantly apart in the space between the walls of the stationary section, to apply the lifting power uniformly and prevent binding between the stack sections.

11. In a stack, a double walled stationary 120 stack section, an extensible section slidable in the space between said walls, a plurality of jackscrews located in said space in driving engagement with the extensible section, and rotating means for the jackscrews 125 located at the base of the stationary stack section, said means including motor driven countershaft and gear devices.

12. In a stack, a stationary double walled section, an extensible section slidable in the space between said walls, elevating jackscrews occupying said space at equidistantly located situations, elevating screw blocks carried by the extensible section and receiving the jackscrews, bearing means for the ends of said jackscrews, and a hood carried

by the extensible section arranged to cover the space between the walls of the stationary section. 10
